FIG. 5

FIG. 2

FIG. 3

FIG. 4

FIG. 1

FIG. 1 is a perspective view of a retractable rope hook for vehicles showing my new design therefor;

FIG. 2 is a side elevation of FIG. 1;

FIG. 3 is an end elevational view as seen from the lefthand side (lines 3—3) in FIG. 2;

FIG. 4 is an end elevational view of the opposite end of FIG. 2 as seen from the righthand side (lines 4—4) thereof; and

FIG. 5 is a bottom plan view as seen from below FIG. 2.

The side elevation opposite that of FIG. 2 is similar thereto except that the open side of the hook is not seen.

I claim:

The ornamental design for a retractable rope hook for vehicles, as shown and described.
